UNITED STATES PATENT OFFICE.

GEORG PODLICH, OF BERLIN, GERMANY.

TYPE-WRITING MACHINE.

SPECIFICATION forming part of Letters Patent No. 722,625, dated March 10, 1903.

Application filed November 19, 1901. Serial No. 82,828. (No model.)

To all whom it may concern:

Be it known that I, GEORG PODLICH, a subject of the King of Prussia, German Emperor, residing at 24 Sophrenstrasse, Berlin, Prussia, Germany, have invented Improvements in Type-Writing Machines, of which the following is a specification.

My invention consists in the features and combination of parts hereinafter described, and particularly pointed out in the claims.

In the accompanying drawings, Figure 1 is an end elevation. Fig. 2 is a plan view. Fig. 3 is a plan view of the plate which carries the device. Fig. 4 is a plan view of a modification. Fig. 5 is a perspective view of part of a type-writer carriage with the device in place. Fig. 6 is a transverse sectional view of the device.

The device consists of a plate *a*, adapted to be attached to a carriage of a type-writer and having a slit *d* and a second slit *e* out of alignment longitudinally with each other. Adjacent the slit *e* bearings or ears *e'* are formed, and in these a shaft *g* is journaled, the said shaft being extended beyond the said ears and having thereon a feeler-finger *b*, which extends from the shaft and has its edge overlying the slit *d*. This feeler-finger is adapted to rest on the paper and be thus prevented from passing through the slit as long as the paper is passing over the plate *a*; but as soon as the end of the paper is reached the feeler-finger will pass down through the slit *d* under the action of the spring *f*, which is coiled around the shaft *g*, and this will cause an arm *c* to be raised from the substantially horizontal position shown in Figs. 5 and 6 to a substantially vertical position, so as to display a visual signal *c'*, carried by the said arm. The position of the device in relation to the paper-roll is shown more clearly in Fig. 6, which also illustrates one way of securing the device in place by means of a spring-clamp *z*, provided on the device, which grips over two

pins *k k* on the carriage, the said clamp being supported on the plate *a*.

I do not wish to limit myself to any particular form of fastener means.

In Fig. 4 I show a joint at *g* in the shaft *g*, so that the feeler-finger *b* may be turned upwardly out of the way when placing the paper in the machine to manipulate the paper in any way.

As shown in Fig. 5, the arm *c* may be bent, so as to avoid striking the releasing-lever of the carriage.

What I claim, and desire to secure by Letters Patent, is—

1. As an attachment for a type-writer, a plate, adapted to be attached thereto, and having two slots therein at *d* and *e* out of line with each other, a shaft *g* extending over the slot *e*, a tongue *b* on the said shaft having its end reaching over the slot *d*, a spring about the shaft tending to force the tongue through the slot and a visual signal on the shaft, substantially as described.

2. In combination with a type-writer carriage, a shaft, a plate adapted to be attached to the carriage and carrying the said shaft, an arm attached to the shaft and carrying a visual signal, a tongue on the shaft to engage the paper, said visual signal being disposed in a horizontal plane when the tongue is bearing on the paper, substantially as described.

3. In combination, a plate adapted to be attached to a type-writer carriage, a tongue, a shaft on the plate having a joint in its length and carrying the tongue and a spring for operating the shaft, the said joint permitting the shaft with the tongue to be turned up, substantially as described.

In testimony whereof I have hereunto set my hand in the presence of two witnesses.

GEORG PODLICH.
